DOUBLE THROW SWITCH

Wilhelm Quante, Wuppertal-Elberfeld, Germany

Application May 6, 1931, Serial No. 535,427
In Germany May 9, 1930

1 Claim. (Cl. 200—5)

The invention relates particularly to throw over switches adapted to control a plurality of lines. Throw over switches are known which are arranged side by side on a common axle. Such switches are likewise known in which the individual levers can be independently operated. Further it is known to construct the switching levers as knife contacts. The invention consists in that these independently operable switching levers are arranged side by side on a common axle and are provided with three pairs of contact knives arranged in cross-shape and engage in contact springs. By the combination of these features it is possible to arrange all terminals as close as possible in order to enable the switch to be used for various purposes, for example as separate throw over switch, as multiple throw over switch, as collector switch, as testing switch, as line selector and the like without long connecting wires. Moreover by this arrangement the terminals are clearly visible and easily accessible.

In order to prevent all interruption of the current flow when changing over from the main line to the branch line, one pair of contact knives, according to the invention, always remains in contact with the coordinate terminal connected to the main line irrespective of the position of the lever.

An embodiment of the invention is illustrated by way of example in the accompanying drawing in which:

Fig. 1 shows the switch in top plan view.

Fig. 2 is a section on line 2—2 of Fig. 1.

Fig. 3 is a section on line 3—3 of Fig. 1.

The casing consists of a base *a* pressed from insulating material, further of a supporting plate *b* also pressed from insulating material, and of a cover *c* of insulating material. Pairs of springs *d'*, *d''* and *d'''* are fixed on the supporting plate *b*. These pairs of springs are connected to the terminals *e'*, *e''* and *e'''*. The main circuits are connected to the terminals *e'''*, whereas lines leading to the substations are connected to the terminals *e'* and those to the central station to the terminals *e''*. An axle *f*, journaled in the side walls of

the base *a*, extends transversely through the casing. The switch levers *h* pressed into the bearing part *g* are mounted side by side on this axle. One pair of each of the cross-shaped contact knives are also pressed into this bearing part *g*. The knives *i*, *k* and *l* are produced by the cross-shape. The knife *l* is wide, so that it remains in contact with the contact spring *d''*, irrespective of the position of the lever. The contact *k* engages the spring *d'''*. Consequently, the official line is switched to the central station. If the lever is thrown upwards, the knife *k* disengages from the spring *d'''* and the knife *i* engages the spring *d'*, so that the official line is switched to the branch station. If the switch lever is in the medium position, both the contact knife *k* and the contact knife *i* are disengaged from both contact springs, so that both the central station and also the branch station are switched out. The fixing of the switch levers *h* is effected by screws *o'*, *o''* and *o'''*. Between screw and switch lever a bar *n* is fixed as desired which, in the example shown interconnects all the cylinders so that, when one switch lever is moved, all the switch levers are actuated. If it is desired to actuate the two extreme cylinders or switch levers together and to leave the middle lever inoperative, the bar *n* is set off over the middle screw *o''* so that only the two extreme cylinders are rigidly connected with the screws *o'* and *o'''*.

On the cover *c* a marking table *m* is arranged, which is divided into two sections, on which the position of the lever is indicated.

I claim:

A throw over switch for a plurality of lines to be switched separately, comprising in combination a common axle, independently actuated pairs of contact knives arranged in cross shape on said axle, angular switch levers connected at one end to said pairs of contact knives, the free arms of said levers constructed in bow shape, spring clips engaging the other end of said pairs of contact knives, and an insulating board carrying said clips.

WILHELM QUANTE.
